United States Patent Office.

MARCUS L. HORTON, OF WINDSOR, VERMONT.

Letters Patent No. 97,296, dated November 30, 1869.

IMPROVEMENT IN BOILER OR OTHER FURNACES.

The Schedule referred to in these Letters Patent and making part of the same.

To all persons to whom these presents may come:

Be it known that I, MARCUS L. HORTON, of Windsor, in the county of Windsor, and State of Vermont, have invented a new and useful Improvement in Furnaces for the Combustion of Fuel; and I do hereby declare the same to be fully described in the following specification, and represented in the accompanying drawings, of which—

Figure 1 is a horizontal section of my improved furnace, such section being taken through the grate.

Figure 2 is a longitudinal section;

Figure 3, a transverse section; and

Figure 4, a front elevation of such furnace.

Figure 5 is a rear view of one of its fire-proof linings or walls.

On February 18, A. D. 1868, Letters Patent No. 74,536, were granted to me for an improvement in furnaces. The furnace shown in such patent has a rotary grate, but in my present furnace I have stationary grates, having tubular bars arranged parallel, and having their ends open, and lateral ducts to open from one to the next of such tubular bars.

I also have tenon and socket branch pipes to each longitudinal tubular grate-bar.

Furthermore, I have a divisional chamber between the two grates, and underneath the central air-discharging partition, which separates the fire-chamber, such divisional chamber being closed at its front end, and made to open at its rear into the chamber or space which extends underneath the side and back walls of the furnace.

In the drawings—

A A' denote a furnace or chamber of combustion, divided along its middle by a wall or fire-brick partition, B, which has a series of parallel longitudinal channels, a a a a, made through it, horizontally.

It also has a series of channels, b b b b, made vertically in it, and from the upper horizontal channel down to the bottom of the partition, and crossing and opening into the other horizontal channels.

Furthermore, numerous holes or educts, c c, lead in opposite directions out of each of the said horizontal channels.

At their lower ends, the vertical channels open into a long chamber, C, which is closed in front and open at its rear, and is arranged between two grates, D D, disposed at the lower part of the fire-place.

Below the said grates and the chamber C, is the ash-chamber E.

Directly over the ash-chamber, and in front of the grates, is an air-channel or space, F, into which the horizontal bars of the grates, at their front ends, open.

The space F is entirely separate from another chamber or space, G, which surrounds the ash-chamber on its sides and back, extends up to a level with

the upper surfaces of the grates, and is arranged underneath the back and side-walls or lining H I I of the fire-place.

Each of the said linings H I I is channelled on its back, both vertically and horizontally, in manner as shown at c' c' c' c' d' d' d' d', and is also provided with holes e, to lead from such channels, or the horizontal ones, into the fire-place.

The space F is provided with one or more air-inlets, e', at its front, which have a slide-valve or register, f, applied to it or them, so as to enable such to be closed, more or less, as circumstances may require.

Furthermore, there are two door-ways or mouths, g g, to the fire-place, each being provided with a door, h.

Each of the grates is composed of a series of long tubes, i i i i, arranged parallel to one another.

Each of such tubes has tubular male and female branches, k l, projecting from its opposite sides, and opening out of it, each branch on one side being just long enough to receive and fit to the other on the opposite side, the same being so that the branches of one tube may be extended into those of the next one, as a tenon fits into a mortise.

The middle chamber or channel C is also provided with such female branches m, projecting from it in opposite directions, to receive the male branches of the next adjacent grate-bars or pipes, and so that they may open directly into the said chamber.

With my furnace, so made, fuel may be burned on either or both the grates, as circumstances may require.

The air received into the chamber or conduit F, will pass through the grate-bars, and into the chamber or space about the ash-chamber, thence it will flow into the chamber C, and the said space about the ash-chamber, such air will pass up into the partition, and the side and back walls or linings of the fire-place, and from thence will be discharged into the fuel, and the flame and smoke which may arise therefrom. In its passage through the grates, and about the sides of the ash-chamber, and up into and through the partition, and linings, the air will become heated, and in this state will greatly promote combustion of the fuel and the gaseous products thereof.

I would remark, that in the furnace, as represented in my said patent No. 74,536, I have exhibited fire-brick or fire-clay linings, containing vertical and horizontal pipes, of metal; but in my present furnace, the linings are without any such metallic pipes, but are simply channelled, both horizontally and vertically, the side and end linings being made with the channels in their rear falls.

The dispensing with the metallic pipes renders the

linings not only cheaper, but better, as they are not liable to be cracked in consequence of being expanded or contracted, on the iron pipes, by the heat, or by the pipes being contracted or expanded within them.

Now, I herein make no claim to making the lining of a fire-place with vertical channels, only opening into the fire-place; nor do I herein claim the combination and arrangement of the iron pipes, both horizontal and vertical, with a fire-brick lining moulded on them.

I make no claim to the introduction of air into a hollow grate, and thence into a chamber about the ash-chamber, and next into and through channelled linings of a fire-place, and from thence into the fire-place, or fuel-chamber thereof; but

What I do claim, in the above-described furnace, is as follows:

1. The combination and arrangement of the channelled partition B, the chamber C, the receiving-conduit or space F, the two hollow grates D D, and the chamber or space G surrounding them, and opening into the central chamber C, as set forth, the whole being constructed substantially as explained.

2. The tubular grate-bars, with the male and female branches extending from them, constructed and arranged as specified.

MARCUS L. HORTON.
